UNITED STATES PATENT OFFICE.

JOHN C. SCHRICKER, OF DAVENPORT, IOWA.

TRACK FOR ROADWAYS.

1,318,332.

Specification of Letters Patent.

Patented Oct. 7, 1919.

Application filed July 23, 1919. Serial No. 312,703.

To all whom it may concern:

Be it known that I, JOHN C. SCHRICKER, a citizen of the United States, and a resident of Davenport, in the county of Scott 5 and State of Iowa, have invented certain new and useful Improvements in Tracks for Roadways; and I do hereby declare that the following is a full, clear, and exact description thereof, reference being had to the 10 accompanying drawings, and to the letters of reference marked thereon, which form a part of this specification.

This invention relates to improvements in tracks for roadways and the like and consists of the matters hereinafter described 15 and more particularly pointed out in the appended claims.

The object of the invention is to provide an efficient and durable track for the traffic 20 lines of roadways upon which may run the tread of vehicle wheels.

This object together with the various advantages of the invention will be made more apparent as I proceed with my specification.

25 In the drawings:—

Figure 1 illustrates a cross section through a roadway to which my improved track has been applied.

Fig. 2 illustrates a longitudinal section 30 through one of the tracks, the plane of the section being indicated by the line 2—2 of Fig. 1.

Fig. 3 illustrates a transverse section 35 through one of the tracks, the plane of the section being indicated by the line 3—3 of Fig. 2.

Fig. 4 illustrates a perspective view of a block forming a sectional part of the improved track.

40 Referring now in detail to that embodiment of the invention, illustrated in the accompanying drawings:—5 indicates as a whole, an arched roadway which may be paved or unpaved, and 6 indicates my improved tracks embedded therein. The said tracks extend longitudinally of the roadway and are spaced apart a distance equal to the wheel gage of standard vehicles.

Each track 6 is made up of a plurality 50 of sections in the form of elongated blocks 7, placed in overlapping end to end arrangement, the ends of said blocks having interlocking parts to prevent lateral displacement. In Fig. 4 I have shown a perspective 55 view of one of said blocks which I prefer-

ably make of reinforced concrete or other suitable material. As all the blocks are similar in shape, a detailed description of one will suffice.

The block 7 is preferably rectangular in 60 form, of a length greater than its width and of a thickness less than said width. At one end, on the top side of said block, is an extension 8, and at the other end of the bottom side of said block is an extension 9 65 which is adapted to be overlapped by the extension 8, of an adjacent abutting block 7. In the top surface of the bottom extension 9 is provided a longitudinally arranged 70 groove 10, in which a rib 11 on the overlapping top extension of the adjacent block 7 is adapted to engage. By this construction, that part of the extension 9 and 8 respectively, defining the side walls of the groove 10 and rib 11, provide co-acting 75 shoulders which lock the lapping extensions together against lateral movement, so that the blocks in the track will always be in alinement.

Preferably, I provide in the top surface 80 of each block, a longitudinal concavity or shallow groove 12, in which vehicle wheels will travel and be guided against running off the track. Also, for the purpose of drainage, so as to prevent the accumulation 85 of water in the grooves 12, I provide at the middle and on each side of the top of each block, transverse grooves 13 which open into said grooves 12.

To insure strength against breakage, I reinforce each block with metal in the form 90 of a woven or expanded metal mat 14, which, as shown in Fig. 2, extends from the middle of the top extension 8, obliquely downward through the body of the block and into the 95 middle of the bottom extension 9. This mat which is entirely embedded in the block, is invisible upon observation of an individual block and provides a maximum of tensile strength for each block, so that it 100 withstands all stresses imposed upon it when in use for its intended purpose.

In laying the blocks end to end, to form a track, I preferably apply to the engaging 105 surfaces of the overlapping extensions, a joint filler of a pitchy or tarry mixture, as shown at 15 in Fig. 2 and Fig. 3, which holds the blocks together in an end to end position with respect to each other, and allows for the expansion and contraction of the 110

blocks in track, so that there will be no upheaval of the blocks due to atmospheric changes.

A track made up of my improved blocks, 5 possesses many advantages. It may be used in connection with either macadamized or gravel roads, and is practical and economical for its intended purpose. It eliminates ruts and chug holes that provide undue 10 pounding and vibration wear in vehicles, and as the blocks making up the track are easy to lay in place, the cost of construction is but a small part of that of a fully paved road. The track will amply drain itself of 15 water, which will carry with it such dirt as lodges therein, so that when the roadway is again dried out, no dust clouds arise from passing vehicles.

While in describing my invention, I have 20 referred to certain details of form, construction and arrangement of parts, I do not wish to be limited thereto, except as may be pointed out in the appended claims.

I claim as my invention:

25 1. A track for a roadway, comprising, a plurality of blocks arranged end to end, each block having end extensions, the end extension on one block being adapted to overlap the end extension on the abutting block, said extensions having interengaging parts adapted to lock said blocks against lateral movement, but permitting of an endwise expansive and contractile movement.

30 2. A track for a roadway comprising, a plurality of blocks arranged end to end, each block having end extensions, the end extension on one block being adapted to overlap the end extension on the abutting block, said end extensions having interengaging parts adapted to lock said blocks against lateral movement, but permitting of an endwise expansive and contractile movement of said blocks, each block having a longitudinal groove in its top surface which 35 forms a continuation of a like groove in the abutting blocks.

35 3. A track for a roadway comprising, a plurality of blocks arranged end to end, each block having end extensions, the end extension on one block being adapted to overlap the end extension on the abutting block, said end extensions having inter-

engaging parts adapted to lock said blocks against lateral movement, but permitting of an endwise expansive and contractile movement of said blocks, each block having a longitudinal groove in its top surface which forms a continuation of like grooves in the abutting blocks, and having transverse grooves at their middle which open into said 60 longitudinal grooves. 55

4. A track for a roadway comprising, a plurality of blocks arranged end to end, each block having end extensions, the end extension of one block being adapted to overlap the end extension on the abutting block, said end extensions having interengaging parts adapted to lock said blocks against lateral movement, and reinforcing means embedded in said block and extending 70 from one to the other extension thereof. 70

5. A block for the purpose described, comprising a rectangular body having a shallow groove in its top surface and a top extension at one end and a bottom extension at 75 its other end, the said top extension being adapted to overlap the bottom extension of an abutting block, one of said extensions having a groove and the other of said extensions having a rib, the rib on one extension being adapted to engage in the groove in the other extension of an abutting block. 80

6. A block for the purpose described, comprising a rectangular body having a shallow groove in its top surface, and a top extension at one end and a bottom extension at its other end, the top extension having a rib on its bottom surface, which is adapted to engage in a groove in the top surface of a bottom extension when a plurality of said 90 blocks are arranged end to end in abutting relation, and a reinforcing metallic mat in said block, extending obliquely through said body, and into said end extensions at their middle. 95

In testimony, that I claim the foregoing as my invention, I affix my signature in the presence of two witnesses, this 18th day of July, A. D. 1919.

JOHN C. SCHRICKER.
